TOILET FLUSHER

William F. Hagedorn, St. Louis, Mo.

Application December 3, 1934, Serial No. 755,707

4 Claims. (Cl. 221—101)

My invention relates to improvements in a flushing apparatus for water closets and the like.

The main object of my invention is to provide an apparatus of this kind in a simple, inexpensive and compact form and which includes a minimum of working and wearing parts so as to simplify installation, to be of neat appearance and to give long trouble free operation.

Another object is to provide a toilet flushing apparatus embodying a novel and advantageous form of operation valve arranged for manual operation as it is opened to flush the bowl and with a mechanical latch to hold it in opened position through a period of time sufficient to pass enough water to thoroughly flush said bowl.

Another object is to provide a novel means for thereafter releasing the said mechanical latch and causing the valve to automatically reseat itself and shut off the flow of water, the said means comprising a carrier element having propeller vanes or blades causing it to rotate and rise up a threaded stem as the water rushes past and to finally engage and release said latch.

A further object is to provide a novel means for forming the necessary water seal or after fill for the bowl.

With these and other objects in view as may appear in the course of the following specifications attention is directed to the accompanying drawing as forming a part thereof and as illustrating a practicable embodiment of my invention.

In the drawing:

Figure 1 is a longitudinal section through my apparatus showing water inlet means and a part of the bowl in dotted lines and showing the valve in closed or inoperative position.

Figure 2 is a cross section along the line 2—2 in Figure 1.

Figure 3 is an enlarged longitudinal section through the valve and its operating mechanism.

Referring now with more particularity to the drawing in carrying out my invention I provide an elongated tubular or cylindrical casing designated generally at 5 and being shown in the drawing as formed of an upper end section or casting 6 of substantially L-shape and a lower end section or shell 7 and the two being joined by a draw nut 7a threaded on the upper end section 6 at 8. However the whole casing may if desired be formed of one integral casting or made up in any other suitable form. A nipple or water inlet 9 is threaded at 10 over the lower end of the casing and has a tapped opening 11 to receive a pipe A leading city water or water under pres-

sure to the casing. A spider or spoked ribs 13 supports a hub 14 centrally in the lower end of the casing and this hub has an upwardly opening tapped socket 15 for a purpose to be described.

The L-shaped formation of the upper end section 6 of the casing provides a laterally extending outlet 16 which is attached by a draw nut 17 to the inlet B of a conventional water closet or toilet bowl C shown in dotted lines. Inwardly of and just below this outlet 16 a downwardly flaring and angular valve seat 18 is formed and same as is shown falls just at the lower end of the upper casing section or casting 6. Immediately above this seat 18 the casing is almost closed by a wall or shoulder 19 which is recessed out on its lower edge to curve nicely out to the outlet 16 as indicated at 20. A chamber 21 is thus formed at the upper end of the casing 5 and is closed except for a restricted opening 22 adjacent the outlet 16 and formed by terminating the shoulder 19 just short of the side of the casing over said outlet. The shoulder 19 has an aperture 23 cut through its center and concentric with the casing as a whole and a valve push rod 24 is slidably mounted through this aperture up and out the upper end 25 of the casing through a packing gland 26 and is provided at its exposed upper end with a knob 27. In normal position the lower end 28 depends down through the center of the valve seat 18.

A flush valve 29 of soft rubber or other suitable material is provided and has a tapering end 30 adapted to seat against the seat 18 and shut off the flow of water therethrough. The valve will be normally pressed tightly to its seat by the pressure of water in the lower portion of the chamber as will be readily evident. The valve is attached to a base or body 31 by a screw 33 passed through the conical bottom 34 of the valve into said base and holding the valve tightly to a flaring socket 35 in said base. The lower end 28 of the push rod 24 normally rests on the screw 33 and by pushing downward on the knob 27 it will be seen that the valve may be pushed from its seat so that water will flow through the casing and out the outlet 16 into the toilet bowl C and flush the same.

A stem 36 is threaded at its lower end 37 in the socket 15 in the aforesaid hub 14 and extends vertically upward therefrom through the center of the casing as shown up to a point near the valve seat 18 and the enlarged upper end 38 of this stem plays freely in a socket or bore 39 in the valve base 31 to pilot said valve and allow

the necessary vertical play of the valve while maintaining it in proper alignment with its seat. A pair (more or less) of latches 40 are hinged at their upper ends 41 in slots or notches 42 in said valve base 31 and hanging free of their own weight are balanced to swing inward toward the stem 36 at their lower ends whereby the hooks 43 as the valve is pushed down will slip over and engage the shoulder 44 below said enlarged upper end 38 of the stem and will thus hold the valve 29 in opened position (Figure 3). A carrier member or release block 45 is provided and same has an axially extended bore 46 adapted to clear and freely receive the stem 36 on which this member is mounted. The said stem has square or worm threads 47 throughout all of its length except for clear and reduced upper and lower end portions 48 and 49. Said bore 46 also clears this threaded length of the stem as shown. Wings or blades 50 are hinged at 51 in slots 52 cut at diametrically opposite points through the walls of the carrier member 45 and the outer ends 50a of these wings are twisted or inclined relative to the axis of the member whereby they serve or act as propeller blades in a manner to be described. The opposite ends of the wings have small short fingers or teeth 53.

In the normal position of the parts the carrier member 45 rests at the lower end of the stem 36 against a rubber bumper washer 54 and the wings 50 of their own weight hang down almost flat against the sides of the member as shown in Figure 1. Now as the valve 29 is pushed open and locked by the latches 40 and water rushes through the casing as set forth above the force of the water will first raise or swing the wings 50 upward and outward and impinging against the twisted ends 50a thereof will impart a rotating motion to the carrier member 45 and will at the same time urge the same upward on the stem 36. In this substantially horizontal position of the wings 50 the fingers 53 are swung inward and will then engage the threads 47 on the stem 36. These threads are so cut that the rotary movement thus imparted to the member 45 will cause it to "screw" up the stem 36 until it reaches the upper extremity of the threaded portion thereof. In this position the tapered end 55 of the carrier member strikes the lower ends of the latches 40 and forcing the same apart releases the hooks 43 from the shoulder 44 and allows the valve to close under pressure of the water in the casing. At the same time the upward flow of water being shut off the wings 50 fall back to their downward position releasing the fingers 53 from the threads 47 at the clear upper end 48 of the stem and the carrier 45 falls back of its own weight to its starting position.

During the time the valve 29 is open water rushes into the bowl C and flushes it thoroughly and at the same time a part of the water passes up through the opening 22 into the chamber 21 and as the valve again closes this water runs slowly out of the chamber and out through the outlet 16 into the bowl to form the necessary after fill or water seal. To prevent air from being trapped in the chamber 21 as it fills a small tube 56 is extended from the outlet 16 up to the top of the chamber as shown. From the foregoing it will be apparent that a push on the knob 27 sets the parts in operation so that a quantity of water runs into the bowl sufficient to completely flush the same after which the water is automatically shut off and the water seal provided.

The operation is simple and positive and a minimum of working parts and valves are used thus increasing the useful life of the device. An important feature is the compactness of the device and it will be evident that the casing may be very small since very little storage or tank space is required. The casing also lends itself to any ornamental finishing or formation and may even be concealed in the wall entirely hidden.

While I have herein set forth a certain preferred embodiment of my invention it is understood that I may vary from the same in minor structural details so as best to construct a practical device for the purposes intended, not departing from the spirit of the invention and within the scope of the appended claims.

I claim:

1. In a device of the kind described, a tubular casing having a water inlet at one end and a laterally opening water outlet some distance from the inlet, the other end portion of the casing being entirely closed except for a restricted opening communicating with the water outlet, a valve seat formed adjacent the outlet, a valve seated in the valve seat, a push rod slidably mounted in the casing and adapted to push the valve away from its seat in the direction of the inlet, a threaded stem mounted longitudinally in the casing from the inlet end to the valve and the said valve being slidably mounted on the stem, a shoulder formed on the stem adjacent the valve, latches pivoted on the valve and adapted when the valve is opened to engage the said shoulder and hold the valve in this position, and means operable upon the said threaded stem for automatically disengaging the said latches and reseating the valve.

2. In a device of the kind described, a tubular casing having a water inlet at one end and a laterally opening water outlet some distance from the inlet, the other end portion of the casing being entirely closed except for a restricted opening communicating with the water outlet, a valve seat formed adjacent the outlet, a valve seated in the valve seat, a push rod slidably mounted in the casing and adapted to push the valve away from its seat in the direction of the inlet, a threaded stem mounted longitudinally in the casing from the inlet end to the valve and the said valve being slidably mounted on the stem, a shoulder formed on the stem adjacent the valve, latches pivoted on the valve and adapted when the valve is opened to engage the said shoulder and hold the valve in this position, and means for automatically disengaging the said latches and reseating the valve, the same comprising a carrier member freely mounted on the said stem, angularly set and twisted wings pivoted on the carrier and normally hanging free and downward against the member but adapted by the rush of water through the casing to swing outward and impart a rotary movement to the carrier member, the said wings having small fingers at their ends adapted as the wings move outward to mesh with the threads on the stem and cause said rotary movement of the carrier to move the same up the stem, and the end of the carrier being tapered to engage and release said latches and as the carrier reaches the end of the stem.

3. In a device of the kind described, a tubular casing having a water inlet at one end and a laterally opening water outlet some distance from the inlet, the other end portion of the casing being entirely closed except for a restricted open-

- ing communicating with the water outlet, a valve seat formed adjacent the outlet, a valve seated in the valve seat, a push rod slidably mounted in the casing and adapted to push the valve away from its seat in the direction of the inlet, a threaded stem mounted longitudinally in the casing from the inlet end to the valve and the said valve being slidably mounted on the stem, a shoulder formed on the stem adjacent the valve, latches pivoted on the valve and adapted when the valve is opened to engage the said shoulder and hold the valve in this position, and means for automatically disengaging the said latches and reseating the valve, the same comprising a carrier member freely mounted on the said stem, angularly set and twisted wings pivoted on the carrier and normally hanging free and downward against the member but adapted by the rush of water through the casing to swing outward and impart a rotary movement to the carrier member, the said wings having small fingers at their ends adapted as the wings move outward to mesh with the threads on the stem and cause said rotary movement of the carrier to move the same up the stem, and the end of the carrier being
- tapered to engage and release said latches and as the carrier reaches the end of the stem the threads on the stem terminating considerably short of both ends thereof whereby the fingers in the wings will turn free as the carrier actuates the latches and allow the wings to swing back inward and the carrier to return to starting position.
4. In a device of the kind described, a tubular casing having spaced water inlets and outlets, a valve seat formed adjacent the water outlet, a valve seated in the valve seat and normally shutting off the outlet, means mounted in the casing and adapted to move the valve away from its seat in the direction of the inlet, a threaded stem mounted in the casing from the inlet to the valve, the said valve being slidably mounted on the stem, a shoulder formed on the stem adjacent the valve, latches mounted on the valve and adapted when the valve is opened to engage the said shoulder and hold the valve open, and means operable on the said threaded stem for automatically disengaging the said latches and freeing the valve.
